APPARATUS FOR SPINNING SOLUTIONS OF CELLULOSE ETHERS OR ESTERS

Application filed March 27, 1928, Serial No. 265,158, and in France June 22, 1927.

It is known that the spinning of cellulose ethers and esters is carried on in closed chambers or cells, in order to facilitate the collection and recovery of the volatile solvents employed.

It is also known that, with a view to facilitating the evaporation of said solvents, said chambers or cells are usually heated by suitable means.

- 10 These arrangements are not a source of inconvenience when the spinning proceeds from below upwards, but, on the contrary, when the spinning proceeds from above downwards, the spinning nozzle is disposed 15 right in the top part of the chamber or cell and thus in the hottest zone, the temperature of which upper zone is very high. Under these conditions, the cellulose issuing 20 from the spinning nozzles is suddenly raised to this very high surrounding temperature, the effect of which is either to increase the fluidity of the spinning material and lower its viscosity, or to set up rapid evaporation 25 of the solvent.

25 In all cases the resulting threads are defective and of inferior quality.

The present invention consists in providing means for preventing these inconveniences.

- 30 In the first place, according to the invention, the harmful effects of said elevation of temperature are considerably lessened by disposing points of entry for cold air by the side of the spinning nozzle, in the top of 35 the chamber, in such a way that the cold air, drawn towards the centre of the chamber, flows in a downward direction whereby the threads, as they issue from the spinning nozzle, are subjected to a cold circumambient medium.

40 However, in order that this arrangement may be completely efficacious, it is necessary to prevent any considerable amount of hot air ascending from the bottom of the cell 45 into the top. With this object, according to the invention, a diaphragm is disposed, at a suitable height, so as to divide the interior of the cell into two compartments and is mounted in such a way as to allow of the 50 passage of the threads.

If, with a device of this kind, the aspiration drawing the air laden with vapours of solvents from the cell into the recovery apparatus is properly regulated, the hot air will not reascend from the zone below the 55 diaphragm into the upper zone, but on the contrary, the cold air of the upper zone will be drawn through the hole provided, in the diaphragm, for the passage of the thread; and this cold air will pass into the lower 60 zone, thereby facilitating the passage of the thread. In this manner the spinning nozzle and the first portion of the path traversed by the thread can be maintained at the same 65 temperature as the outside air.

By way of example, a description will now be given of a spinning chamber provided with the improvements the principle of which has just been enunciated.

In the accompanying drawing, Fig. 1 is 70 a vertical section through said chamber, Fig. 2 a plan of same, Fig. 3 a partial vertical section showing the diaphragm in the open position, and Fig. 4 a plan of the diaphragm.

75 Holes $EE^1 \dots E^7$ are pierced in the top AB of the cell ABCD, for the admission of cold air. These holes, in convenient number, may be disposed circularly round the spinning nozzle F, situated in the centre of the top AB of the cell. The thread, represented diagrammatically by H, travels from above downwards and winds on the bobbin I located in the lower part of the cell. The aspiration is preferably effected on a level 80 with said bobbin I.

The diaphragm is indicated at MN. In the example under consideration, the diaphragm is horizontal, and is composed of two portions, namely a fixed member MP, 90 and another member PN adapted to pivot on a hinge P and resting, by means of its edge N, on a projection O carried by the wall AC of the cell.

95 As can be seen in Fig. 4, the pivotal member PN of the diaphragm is provided with a notch TRS of such a shape that, when the apparatus is started, in commencing to spin, the movable member PN can be lowered and still leave room for the passage of the 100

thread. In order to start the apparatus, this movable member is raised into the position shown in Fig. 3.

After the apparatus is started, the triangular notch TRS is closed, by an easily constructed and simple device, consisting of a sliding or rotating member, in such a way that only the small aperture necessary for the passage of the thread is left open in the diaphragm.

10 The heating may be effected in any part whatsoever of the zone beneath the diaphragm.

15 The device affords the advantage of keeping the first portion of the thread in continuous contact with cold air, this latter merely absorbing the vapours (of the solvents) liberated in this first portion of the path of the thread. On the other hand, in 20 the absence of a diaphragm, this portion of the thread travels in hot air, and, in the case of solvents whose vapours are lighter than air, is surrounded by an atmosphere highly charged with vapours.

25 Certain operations, such as drawing or stretching, can be carried out, under particularly favourable conditions, in a vapour-laden medium. The presence of the diaphragm enables the intermediate and final 30 portions of the path of the thread to be precisely subjected to these favourable conditions.

Finally, it will be understood that it is possible (and even advantageous in certain 35 cases) to provide not only a single diaphragm but a plurality of diaphragms, disposed at various points in the path of the thread. These enable the temperature, or 40 the density of the vapours with which the air is laden, to be regulated, according to requirements, at various levels in the cell.

I claim:

1. Apparatus for use in spinning artificial thread, comprising a spinning cell, means 45 dividing the interior of the cell into superimposed zones adapted to be traversed successively by the spun thread, a spinning nozzle in the upper zone, means for admitting air to the uppermost zone about the spinning 50 nozzle, and means whereby hot air and solvent vapours can be drawn from the lowermost zone.

2. Apparatus for use in spinning artificial thread, comprising a spinning cell, at least 55 one diaphragm dividing the interior of the cell into superimposed zones adapted to be traversed by the spun thread, a downwardly directed spinning nozzle in the upper zone, means for admitting air to the upper zone 60 about the spinning nozzle, and means whereby hot air and solvent vapours can be drawn from the lower zone.

3. Apparatus for use in spinning artificial thread, comprising a spinning cell, at least 65 one diaphragm dividing the interior of the

cell into superimposed zones adapted to be traversed by the spun thread, a downwardly directed spinning nozzle in the upper zone, said diaphragm being constituted by a fixed member and a notched, movable member, 70 means for admitting air to the upper zone about the spinning nozzle, and means whereby hot air and solvent vapours can be drawn from the lower zone.

4. Apparatus for use in spinning artificial 75 threads, comprising a spinning cell, a downwardly directed spinning nozzle in the upper part of the cell, means for admitting cold air about the spinning nozzle and the thread issuing therefrom, and at least one diaphragm in the cell extending partly over the area thereof.

5. Apparatus for use in spinning artificial 80 thread, comprising a spinning cell, a downwardly directed spinning nozzle in the upper 85 part of the cell, means for admitting cold air about the spinning nozzle and the thread issuing therefrom, at least one diaphragm in the cell extending partly over the area thereof, and means whereby hot air and solvent vapours can be drawn from the lower 90 part of the cell below the diaphragm.

In testimony whereof I affix my signature.
MELITTA KLEIN.
